UNITED STATES PATENT OFFICE.

STEPHEN HUSTYAVA, OF NEW YORK, N. Y.

DESIGN FOR AN EASEL.

SPECIFICATION forming part of Design No. 35,020, dated September 3, 1901.

Application filed July 20, 1901. Serial No. 69,161. Term of patent 7 years.

To all whom it may concern:

Be it known that I, STEPHEN HUSTYAVA, a citizen of the United States, residing at Manhattan borough, New York city, in the county 5 of New York and State of New York, have invented and produced a new and original Design for an Easel, of which the following is a specification.

My invention relates to a new and original 10 design for an easel, and is illustrated in the accompanying drawing, which is a perspective view of the easel.

The leading features of my design reside in an easel having a straight or right-lined base-rod and side rods commencing at each ex- 15 tremity of the base-rod, the portion of each side rod immediately adjoining the base-rod forming a rearwardly and upwardly extended stretch or section, the side rods being bent at 20 the top of these rearwardly-extended portions at substantially right angles thereto, forming upwardly and forwardly extended stretches, another angle being formed at the upper end of the upwardly and forwardly extended side 25 portion, a third angle formed at the lower end of a downwardly-extended portion, and a downwardly and forwardly extending stretch commencing at the said third angle and termin- 30 ating in a semicircular or approximately semicircular portion, the side rods being duplicates of each other.

In said drawing the base portion $a' a'$ is shown straight or right-lined. At each extremity of this base-rod commences a side or ridge portion. The wire is so bent that each 35 side portion presents three angles. One angle, a^2 , is formed at the upper end of a rearwardly-extended stretch or section of the side. Another angle, a^3 , is formed at the upper end 40 of an upwardly and forwardly extended side portion. Another angle, a^4 , is formed at the lower end of a downwardly-extended portion, and the free ends or the forwardly and down- 45 wardly extended portions are bent into semi-circular or approximately semicircular por- tions, as seen at a^5 .

The design presents an easel having a novel, pleasing, and distinguished appearance.

What I claim as new, and desire to secure by Letters Patent, is—

The design for an easel substantially as 50 herein shown and described.

In testimony whereof I have hereunto set my hand in the presence of two subscribing witnesses.

STEPHEN ^{his} X HUSTYAVA.
